CLAIM

The ornamental design for an IC card connector, as shown and described.

DESCRIPTION

FIG. 1 is a top and rear isometric view of an IC card connector showing my new design;

FIG. 2 is a top view thereof;

FIG. 3 is a bottom view thereof;

FIG. 4 is a front elevation view thereof;

FIG. 5 is a rear elevation view thereof;

FIG. 6 is a right side elevation view thereof, the left side being a mirror image thereof; and,

FIGS. 7-11 are views of another IC card connector, wherein the views of FIGS. 7-10 correspond to those of FIGS. 1-4 respectively, and the view of FIG. 11 corresponds to that of FIG. 12, but wherein FIGS. 7-11 show a different rear portion.

The broken lines, which appear in FIGS. 1-3, 5 and 6 are only for the purpose of illustrating the article in which the design is embodied, with the broken lines marking the rear boundary of the claimed design. The broken lines form no part of the claimed design.
